UNITED STATES PATENT OFFICE.

PETER PETERSEN, OF LOS ANGELES, CALIFORNIA, ASSIGNOR OF ONE-HALF TO EARL L. PARKER, OF LOS ANGELES, CALIFORNIA.

DOOR CATCH AND FASTENER.

Application filed July 20, 1927. Serial No. 207,079.

My invention is a door catch and fastener particularly adapted for hinged doors.

An object of my invention is the construction of a simple device, one element of which 5 may be attached to a door frame or door jamb and the other connected to a door of the hinged type, for example, so that the door may be retained closed against the action of the wind and other minor forces. 10 Another object, in connection with a swinging screen door, is the provision of a resilient stopping device which will allow the door to close without slamming and retain it in closed position.

15 A still further object of my invention is the provision of means which may readily be actuated from one side of the door to secure the elements of the latch together, so as to positively lock the door against being 20 opened from the other side.

In constructing my invention I have a resilient catch made in the form of a ring, with a split on one side, this split portion having gripping jaws. This ring is provided with screw holes for fastening to a 25 door jamb, or the like, and is adapted to catch a screw eye which may be attached to the associated door. Transverse notches are formed in the eye, and the jaws allow the 30 eye to pass therethrough and engage in the notches, thus holding the door from swinging open when it has been once closed. The resilient jaws also retard the action of the door when it swings closed, by engaging the 35 end of the eye and preventing slamming.

In order to lock the door closed a segmental bolt having a handle is slidably mounted inside of the ring, preferably traveling in a circumferential groove. This 40 bolt is adapted to pass through the eye of the screw-eye and positively lock the door against being opened from the side thereof opposite that upon which the device is mounted.

45 My invention is illustrated in the accompanying drawings, in which:

Figure 1 is a perspective view of a door and frame with my door catch and fastener attached.

50 Figure 2 is a side elevation of the device, showing its engagement with the screw-eye.

Figure 3 is a vertical central section through the catch and screw-eye with the segmental locking bolt shown in elevation.

55 Figure 4 is a horizontal section on the

line 4—4 of Fig. 2 in the direction of the arrow.

Figure 5 is an edge view of the screw-eye, illustrating the latching grooves.

A clamping ring, designated generally by 60 the numeral 11, is formed of resilient metal, this being a flat strip and having inturned lugs 12 with perforations 13 therethrough for attaching screws, this device being intended for attachment to a door jamb or 65 the like. The ring is split, as indicated at 14, and has a pair of outwardly extending jaws 15, these jaws having a relatively wide mouth 16 and a contracted throat 17.

The ring 11 has a groove 18 with an ar- 70 cuate slot 19 formed therein, and in this groove is fitted a segmental bolt 20 having a handle 21 integral therewith and extending through the slot 19. This bolt is preferably made of stiff wire and has a guide 75 end 22 in the lower part of the ring. The bolt, the handle and the end 22 is preferably made of resilient material to fit snugly in the slot. The screw-eye 23 has a threaded end 24 and an eye end 25, and is formed 80 with transverse upper and lower grooves 26 extending across the eye, preferably on the screw side of the eye. This screw-eye is intended to be secured to a door and to have 85 the head in which the eye is formed horizontal so as to pass through the jaws 15.

The manner of operation and functioning of my door catch and lock is substantially as follows:

When the door is swung closed the first 90 action is for the head of the screw-eye to impinge against the jaws 15, which jaws, being of resilient material, are pressed inwardly. The throat is of less width than the thick part of the head, therefore, this causes 95 an immediate slowing up in the motion of the door and prevents a slamming action. The wide part of the head, however, slips through the jaws until the throat engages in the notches 26 of the screw-eye, as shown 100 in Figs. 2 and 3. This is sufficient to prevent the door from being blown or accidentally opened, as the jaws being mounted on the resilient ring are sufficient to retain the door closed.

If it is intended to fasten the door, the handle 21 is given an upward movement in the direction of the arrow 27 of Fig. 3, this handle traveling in the slot 19 so that the bolt end 20 extends downwardly into the eye 110

of the screw-eye, thus locking the ring to the eye as shown in Figs. 2 and 3, and preventing opening of the door. The unfastening is by reversing the movement of the handle. 21
5 It is obvious that the bolt end may be on the lower part so that movement of the handle downwardly will thrust the end of the resilient wire formed of the elements 20, 21 and 22 upwardly through the eye of the 10 screw-eye.

While I have illustrated my invention as a simple device suitable for ordinary household doors, it is to be understood that it may be made in different sizes and suitable 15 for either hinged or for sliding doors, and that the ring part of catch may be secured either to the door or to the door jamb, whichever is most convenient.

Various changes may be made in the principles of my invention without departing 20 from the spirit thereof, as set forth in the description, drawings and claims.

I claim:

1. A door catch and fastener comprising 25 in combination a ring like structure having a split in one side, means to secure said ring to a fixed structure, an eye attached to a movable structure, the eye passing through the said split, and a bolt slidably mounted in the 30 ring and engaging in the eye.

2. A door catch and fastener comprising in combination a ring having a split in one side with jaws at the split, means to secure 35 said ring to a structure, an eye having a head with means to secure the eye to another structure positioned to have the head pass between said jaws and to be engaged thereby, and a curved bolt fitted inside the ring and shiftable to pass through the eye.

40 3. A door catch and fastener comprising in combination a resilient ring having a split in one side and jaws on opposite sides of the split, a screw having a head with an eye therethrough, the ring and the screw being adapted for attachment to a door and 45 door jamb, the head of the screw passing through the said jaws and being engaged thereby, and a curved bolt fitted in the ring and 50 slidably to engage in the eye of the head.

50 4. A door catch and fastener comprising in combination a resilient ring having a split on one side and jaws on opposite sides of the split, said jaws having a contracted 55 throat, a screw having a head with notches on opposite sides of the head and an eye

extending therethrough perpendicular to said notches, the screw and the ring being adapted for attachment to a door and door jamb, the head of the screw fitting between the said jaws and said jaws engaging in 60 the notches of the head, said ring having a groove, a curved wire fitted in said groove, one end of the wire forming a bolt and adapted to pass through the eye of the head, and means to impart rotary movement to 65 said wire relative to the ring.

5. A door catch and fastener comprising in combination a resilient ring having a transverse split on one side with jaws on opposite sides of the split extending outwardly 70 from the ring, said jaws having a contracted throat, the ring having an internal groove and a slot through the groove, a wire fitted in the groove and having a handle extending through the slot, one end of the wire forming 75 a locking bolt and the other end forming a guide end, a screw having a head with an eye therethrough, the head being adapted to pass through the said jaws and to be engaged by the throat, and means to attach 80 the screw and the ring to a door and door frame.

6. In a door catch and fastener comprising in combination a ring of resilient material having a transverse split on one side and 85 outwardly extending jaws, said jaws having a wide mouth and a contracted throat, the ring having a circumferential groove with a slot in the groove and having inwardly turned lugs with apertures therethrough for 90 securing screws, a wire fitted in the said groove and conforming to the curvature thereof, with a handle extending through the slot, the said wire being partly rotatable in the ring with one end adapted to form 95 a bolt and extend across said jaws, the other end forming a guide end on the opposite side of the slot, and means to co-operate with the said jaws and the bolt end of the wire to form a fastening.

7. In a door catch and fastener, a screw having a head with grooves on opposite sides of the head and an eye through the head at right angles to the grooves, the said head being adapted for engagement with resilient 100 jaws, and the eye being adapted for securing a bolt therein.

In testimony whereof I have signed my name to this specification.

PETER PETERSEN.
